UNITED STATES PATENT OFFICE.

ALFRED H. EVANS, OF PORTLAND, MAINE.

KNOCKDOWN CABINET.

No. 920,937.

Specification of Letters Patent. Patented May 11, 1909.

Application filed June 1, 1908. Serial No. 435,869.

To all whom it may concern:

Be it known that I, ALFRED H. EVANS, a citizen of the United States, and resident of Portland, in the county of Cumberland and 5 State of Maine, have invented new and useful Improvements in Knockdown Cabinets, of which the following is a specification.

My invention relates to knock down cabinets or articles of furniture adapted to contain a series of drawers. I have shown my 10 invention embodied in a combination containing two vertical series of drawers but it will be readily understood that it may be embodied in one series or a plurality of series 15 of drawers. It is designed to be capable of separation into its component parts for purposes of transportation, storage, etc. and when desired, capable of being readily re-assembled being in the main entirely free 20 from the necessity of screws, bolts or other fastening devices.

In the drawings herewith accompanying and making a part of this application, Figure 1 is a perspective view of a cabinet fully assembled, parts being broken away to show 25 the bonding posts; Fig. 2 is a plan view of one of the horizontal drawer supporting parts; Fig. 3 is a plan view of one of the side risers adapted to be interposed between each two 30 of the parts shown in Fig. 2; Fig. 4 is an edge view of said risers; Fig. 5 illustrates an edge view of a riser adapted to be used between two series of vertically disposed drawers; Fig. 6 is a plan view of the corner finish strips 35 and Fig. 7 is a transverse vertical sectional view of one of the drawers.

Same letters of reference refer to like parts.

In said drawings A represents the drawer supports provided with a series of vertical 40 holes B adapted to receive the connecting or bonding posts C. Between each two drawer supports A is placed risers D provided with holes E adapted likewise to receive the bonding posts C. These are also 45 provided on the inner edges with projections F which serve as ways upon which the drawers G slide. The drawer supports A are recessed at the corners as shown at H to receive vertically disposed finishing strips I 50 which come flush with the front and side edges of the drawer supports as seen in Fig. 1. At the sides these will be angular and between two series of drawers it would be straight as seen at J. The drawer supports

are preferably open in the center as seen at K thus requiring less material and rendering the cabinet lighter. The top of the cabinet is protected by a suitable cover L. The finish strips are held in place by a series of metal strips M extending from the sides around the 60 front and these are secured to the drawer supports by means of screws or pins N. These strips in addition to holding the finish strips in position add materially to the stability of the cabinet. The front end O of the 65 drawers may be covered with a veneer P which is held in place by one or more headed bolts which pass through the veneer and these bolts Q may also serve as handles if desired in manipulating drawers and are provided with nuts R on the inside. 70

It will be noted that the cabinet may be of any convenient size containing any required series of drawers. Its advantages are that it is exceedingly simple in construction, is 75 comparatively inexpensive and it can be readily taken apart and re-assembled.

Having thus described my invention and its use I claim:

1. In a knock down cabinet, a series of 80 rectangular drawer supports provided with bond receiving holes, a series of risers forming the sides of the cabinet and provided with holes spaced apart from the ends thereof and with ways projecting from the inside, 85 a series of bonding posts adapted to pass through the holes in said drawer support and risers and drawers adapted to slide on said ways.

2. In a knock-down cabinet, a series of 90 drawer supports provided with finish receiving recesses at the front and bond-receiving holes, risers positioned between two adjacent drawer supports and provided with bond receiving holes vertically disposed bonding 95 posts connecting said drawer supports and risers, finish strips positioned in said finish receiving recesses and means for holding said finish strips loosely in position.

In testimony whereof, I have signed my 100 name to this specification in presence of two subscribing witnesses this 20th day of May, 1908.

ALFRED H. EVANS.

In presence of—

MARION RICHARDS,
ELGIN C. VERRILL.
